UNITED STATES PATENT OFFICE.

JOHN HUGO SMITH, OF DETROIT, MICHIGAN.

STAIRWAY.

1,412,899.

Specification of Letters Patent. Patented Apr. 18, 1922.

Application filed May 7, 1920. Serial No. 379,502.

To all whom it may concern:

Be it known that I, JOHN HUGO SMITH, a citizen of the United States, residing at Detroit, in the county of Wayne and State 5 of Michigan, have invented certain new and useful Improvements in Stairways, of which the following is a specification.

This invention relates to stairs and has for its object cast metal stair parts that can 10 be made in the foundry. The parts can be accurately made in the foundry and the stringers can be accurately punched so that the stairs may be easily and quickly assembled together on the job.

15 The stair treads are so constructed as to carry a filler material which can be varied to suit the taste, such as cork, concrete or any other desirable insert.

In the drawings,—

20 Fig. 1 is a vertical longitudinal section of a portion of a flight of stairs showing the parts assembled together.

Fig. 2 is a vertical cross section fragmentary in character, taken on the line 2—2 of 25 Fig. 1.

a represents a casting forming the tread of the stair; *b* a reticulated riser. The tread is provided with upwardly-curved portions *d* and *c* at front and back respectively which 30 form the front and rear boundaries of the space adapted to contain a filler material *e* which may be cork, concrete or some composition material which provides a suitable tread surface. The tread at the front and 35 bottom is provided with a slot *f* while at the rear and top is provided with a slot *g* into which can be slid the reticulated riser *b* to assemble the risers and the tread together. At each side the tread is provided with 40 a depending flange or rib *g* through which bolts *h* can be passed to bolt the tread members to the stringers *l* which are suitably punched to receive these bolts. A reinforcing rib *m* may be used on the under side of 45 the tread when desired.

It will readily be understood that the treads and the risers can be cheaply made

in foundries in standard sizes, the stringers may be properly punched, and the parts sent to the job all ready for assembly. Obviously 50 the assembly of the treads and risers to the stringers is a matter that may be quickly effected, while the tread surface may be easily filled into the container formed in the top of each tread for this purpose. 55

The first corner of the strip is ribbed to prevent slipping and afford a good grip for the foot.

What I claim is:

1. In a stair-way, the combination of a 60 pair of stringers with bolt holes prepared therein at suitable points, a plurality of cast metal treads each having at each end a depending integral flange with holes prepared to register with some of the holes in the 65 stringer, bolts for passing through such registering holes and securing the flanges to the inside of the two stringers to brace and tie the stringers together, each of the treads having a slot at the front and under 70 side and at the rear and upper side, and risers locked into the opposed slots adjoining treads when treads are bolted to the stringers.

2. In a stair-way, a pair of stringers with 75 bolt holes prepared therein at suitable points, a plurality of castings having plate-like members with upwardly turned-up portions at the front and back to form a seat for filler material and having at the ends turned-down integral flanges provided with bolt holes, bolts for passing through said bolt holes of the flanges and the bolt holes of the stringers when in registry to secure the castings to the two stringers and secure the two 80 stringers together, each of said castings provided at the front under side and the top rear side with a riser slot, and risers adapted to engage in opposed slots of adjoining castings when the treads are bolted to the 85 stringers to complete the stair assembly. 90

In testimony whereof I affix my signature.

JOHN HUGO SMITH.
